UNITED STATES PATENT OFFICE.

PAUL THEODOR HÄNEL, OF DRESDEN, GERMANY.

MEANS FOR REMOVING COMPRESSED MATTER FROM CONTAINERS.

Application filed June 11, 1927, Serial No. 198,084, and in Germany June 15, 1926.

When a powdered mass, such as cacao, is compressed there always remain residues in the containers which, owing to the high pressure exerted thereon, become compressed into 5 solid cakes that firmly adhere to the bottoms of the containers and special means are required for the removal thereof.

Various devices are already known for this purpose. Thus one well known device consists of a beam removably fastened to the container and which carries a manually operated threaded spindle which when pressed against the container raises the bottom thereof removing the cake. On reversing the 15 rotation of the spindle the beam is detached and applied to the next vessel to be emptied.

It is also well known to operate said device by hydraulic pressure or mechanical power.

20 Furthermore, devices are already known whereby several containers are emptied simultaneously. These devices are caused either by mechanical or hydraulic power to press simultaneously against the bottoms of 25 the containers.

All these well known devices require more or less time and labor and, if not operated mechanically or manually special hydraulic presses or the like are required that have to 30 be simultaneously operated; as they do not work automatically.

The present invention obviates all these drawbacks by providing the hydraulic press used for the compression of the mass with 35 means which automatically will be impelled by the movement of the hydraulic pressure piston.

My invention will be more fully understood by reference to the accompanying 40 drawing in which similar reference characters denote corresponding parts and in which Fig. 1, is a vertical section of a hydraulic cacao press equipped with my invention; Fig. 2 is a cross section thereof; Fig. 3 is a 45 side view thereof; Fig. 4 is a section on line 1-1 of Fig. 1 and Figs. 5 and 6 detail views of the hydraulic piston and pressure head.

A denotes the stationary frame of the 50 hydraulic press and 19 the piston thereof. Each side of the frame is provided with a number of horizontal guide grooves *a*, arranged in vertically superposed manner. The piston 19 has fixed to its upper end centrally a pressure head 13. Each container or vessel in 55 which the mass is to be compressed has a vertically movable bottom *b* and is provided

with diametrically opposed lateral projections *c* to slidably engage the guide grooves *a* in the frame A. In the present example twelve containers 1-12 are shown, of which six are adapted to be simultaneously in operation for compression of the mass and six to be at the same time in the position for the removal of the compressed mass or cake therefrom. In the position for the compression 60 of the mass six of the containers, as 1 to 6 are stored centrally over the piston 19 or its head piece 13 in a vertical column with removable press blocks 14, 15, 16, 17 and 18, interposed between them while the other containers are supported at the sides of the frame, three at one side, another three at the opposite side, the two sets being vertically displaced relative one another (Fig. 1).

Movably suspended by cords *d* and 70 counterbalanced by weights 54, 55 are two stepped frames formed with beams 38-41, and of which one has steps 42-44 and the other 45-47. Each beam is provided with notches 56-59 and 60-63. The steps 75 42-47 centrally support pressure plates 48-53 adapted to register with the central parts of the bottom of the laterally withdrawn containers 7-12.

Projecting laterally from the head piece 80 13 at diametrically opposite sides are two rigid arms 20, 21 each bearing a roller 20^a. Four substantially T-shaped levers 22-25 are fulcrumed at 26-29 in the frame A and are formed at their free ends with cam portions 30, 32 and carry pivoted fingers 34-37.

The mode of operation of the device is as follows:

In the position shown in Fig. 1 the containers 7-12 are ready for the removal of 95 the cakes while the containers 1-6 containing freshly filled material are ready for compression. When the piston 19 rises to compress the mass in the containers by the heads 13-18, the rollers 20^a of the arms 20 and 21 roll over the cam portions 30-32 of the angular levers 22-25 and thereby swing the latter on their fulcrums 26-29. Through the engagement of the fingers 34-37 in the notches 56-57 the stepped frames are simultaneously moved upwardly carrying with them the pressure plates 48-53 which press against the bottoms *b* of the containers lifting the same together with the cakes deposited thereon. When the rollers 20^a of 100 the arms 20-21 reach the inner corners of the cams 30-33 the bottom of the containers 105

are sufficiently lifted to permit the removal of the cakes. As the hydraulic piston continues to rise the rollers 20^a roll off the inner edges of the cams as a result of which the levers 22-25, and with them the stepped frames and the bottoms of the containers resting on the steps 42-44 are permitted to move downwardly back into initial position. Now these containers can be refilled for the next compression. The levers 34-37 are first swung out of engagement with the notches 56-59 in order that when the piston 19 after the completion of its compression stroke moves downwardly and thereby again swings the levers 22-25 upwardly the stepped movable frames and pressure plates 48-53 be not raised as this would result in the removal of the material from the containers 7-12 before the same has been compressed. On the completion of the compression of the mass in the containers the latter are removed from the column and replaced by the containers 7-12. But before the exchange of the containers one of the stepped frames having the beams 40 and 41 is lowered sufficiently to permit the fingers 36 and 37 to engage the notches 58 and 59 and after the exchange of the containers the other stepped frame having the beams 38 and 39 is lifted to such an extent as to permit the fingers 34 and 35 to engage the notches 60 and 61. Thereupon the operation can begin anew.

It is understood that various other motion transmitting means may be used without departing from the principle of my invention. It is also understood that the removal of the cakes from the containers may be made to take place during the return stroke of the

piston. The operation of the device for the removal of the cakes is advantageously so timed that the same will be completed at the time the piston 19 on its return starts its compression stroke. This is done not because it is desired to avoid the pressure necessary being added to that for the compression of the mass but because during its return stroke the piston may be allowed to move faster than after the expression of the oil from the cacao has begun.

What I claim is:

1. In a device for removing from a container having a movable bottom a mass, such as cacao cake, compressed therein, the combination with a power operated piston for compressing said mass, of means impelled from said piston for raising the bottom of said container.

2. In a device for removing from a container having a movable bottom, a mass, such as cacao cake, compressed therein, the combination with a power operated piston for compressing said mass, of means impelled from said piston and including cam controlled members adapted to act against the bottom of said container.

3. In a device for removing from a container having a movable bottom a mass, such as a cacao cake, compressed therein, the combination with a power operated piston for compressing said mass, of means impelled from said piston and including cam controlled frames and means operated from said frames and acting against said movable bottom to raise the latter during the return stroke of said press.

In testimony whereof I affix my signature.

PAUL THEODOR HÄNEL.
